ATTORNEY

UNITED STATES PATENT OFFICE.

LAURANCE S. STAPLES, OF KANSAS CITY, MISSOURI.

PACKAGING CONTAINER.

Application filed March 16, 1925. Serial No. 15,811.

This invention relates to packaging and serving containers. It is particularly designed to be used in connection with confectionery containing boxes although not necessarily limited thereto.

The primary object of the invention is to provide a compartmental box with an interiorly located cover for each compartment, the covers being so associated that they may 10 constitute handles or supports for the major portions of the box when it is desired to display or serve the contents of the compartments.

The novel details of construction of the invention will be specifically described herein- 15 after, reference being had to the accompanying drawings, in which

Fig. 1 is a perspective view of a box constructed in accordance with my invention showing the cover members, or flaps, for the 20 two compartments in raised position.

Fig. 2 is a perspective view showing the two cover flaps in compartment closing position.

Fig. 3 is a perspective view of the closed 25 box, and

Fig. 4 is a fragmentary, sectional view through one wall of the box and through one end portion of one of the cover flaps.

The invention consists of two rectangular 30 members 1 and 2, each having a bottom wall, two side walls and two end walls. Two adjacent side walls 3 and 4 for the members 1 and 2 are hinged together at their edges as indicated at 5. Projecting inwardly from each 35 hinged edge is a ledge portion 6, for the member 1, and a ledge portion 7 for the member 2. The ledge portions extend the lengths of the members 1 and 2 and at their outer edges they carry closing cover flaps 8 and 9 which are 40 hinged to the ledges 6 and 7 as indicated at 10 and 11. The cover flaps 8 and 9 are wide enough to cover the opening at the top of each member 1 and 2 and they are adapted to be held against accidental movement by stops 45 formed in the box wall for each compartment as indicated at 12 and 13. The stops may be made by pressing in the material so that they slightly project inwardly from the inner faces of the side walls 14 and 15.

50 The material from which the cover flaps 8 and 9 is made will have sufficient flexibility to allow the edges of the cover flaps to be sprung in under the projections 12 and 13. Near the outer edge of each cover flap is an

opening, these openings being designated 16 55 and 17 so that the finger of a person's hand may be inserted in one or both of the openings. This will enable the person handling the box to exert a slight pull outwardly on the cover flap so it will spring out of engagement with 60 the stop to enable it to be swung up beyond vertical position. When the two cover flaps are swung up to the position shown in Fig. 1 the openings 16 and 17 will be substantially in 65 alignment, then the finger may be introduced through both openings, the cover flaps serving at this time for handles or supports for the open trays or compartments so that the contents of the box may be accessible and be served or displayed in a convenient manner. 70

From the foregoing it will be apparent that the box may be conveniently and inexpensively made, that the cover flaps serve a dual purpose in that they normally maintain the contents within the trays or compartments but 75 are movable to positions to provide handles or supports for the trays or compartments and furthermore that the invention is so constructed that candies and the like may be packaged for shipment and dispensed or 80 served from the same container.

While I have shown the compartments as rectangular it is obvious that the box may be made in other shapes.

What I claim and desire to secure by Letters-Patent is:—

1. A box comprising two tray members secured together by a hinge joint, a reinforcement strip comprising a ledge member secured in the open upper end of each tray between the end walls and the side wall adjacent said hinge joint, cover flaps having inner edges hinged to the outer exposed edges of said reinforcement ledge members and adapted to lie wholly within the trays, the outer edges of said flaps adapted for abutting over the said hinge joint, and said flaps having openings adjacent their outer edges to admit means for engaging the flaps to lift the same, said openings being substantially aligned 100 when the flaps are in abutting position, to receive a box supporting means therethrough.

2. A box comprising two tray members secured together by a hinged joint, a reinforcement strip comprising a ledge member secured 105 in the upper open end of each tray between the end walls and the side wall adjacent said hinge joint, cover flaps having inner edges

hinged to the outer exposed edges of said reinforcement ledge members and adapted to lie wholly within the trays, the outer edges of said flaps adapted for abutting over said hinge joint, said flaps having finger-hold openings adjacent their outer edges, said openings being adapted for substantial align-

ment to receive a box supporting means there-through when the flaps are in abutting position, and means adapted to yieldingly retain the flaps in covering position. 10

In testimony whereof, I affix my signature.

LAURANCE S. STAPLES
